UNITED STATES PATENT OFFICE

2,421,700

DIAPHRAGM COVER FOR OXYGEN
REGULATORSJames P. Johnson, Cleveland, Ohio, assignor to
The Aro Equipment Corporation, Bryan, Ohio,
a corporation of Ohio

Application November 23, 1944, Serial No. 564,866

2 Claims. (Cl. 137—156)

1

My present invention relates to a cover for the diaphragm of an oxygen regulator having certain characteristics for protecting the diaphragm against injury.

One object of the invention is to provide protection against sun, rain and foreign objects entering the perforations of the diaphragm cover which would cause rotting, puncturing or other damage to the diaphragm.

Another object is to provide a cover in the form of primary and secondary cover members, the secondary cover member being supported by the primary cover member and spaced therefrom to prevent interference with the entrance of air to the diaphragm through perforations in the primary cover member.

Still another object is to provide the secondary member of such design, size and positional relation to the perforations of the primary cover member that sun and foreign objects cannot enter through the perforations.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Fig. 1 is a side elevation of a demand oxygen regulator to which my diaphragm cover is secured;

Fig. 2 is an enlarged front elevation of the cover per se with a portion of the secondary cover member broken away; and

Fig. 3 is a sectional view through the cover and the diaphragm as well as a portion of the regulator housing, as taken on the line 3—3 of Fig. 2.

On the accompanying drawing I have used the reference numeral 10 to indicate an oxygen regulator housing having the usual oxygen inlet at 12 and mixed oxygen and air outlet at 14. Within the housing 10 there is a demand diaphragm 16 which is operated by inhalation to regulate the supply of air and oxygen to the user. The mechanism of the regulator is not gone into in detail in this application but is of the general type shown in the copending application of Arthur H. Tidd et al., Serial No. 596,006, filed December 20, 1944, and in my copending applications, Serial No. 579,061, filed February 21, 1945, and Serial No. 579,062, filed February 21, 1945.

A primary cover member 18 is provided for the diaphragm 16 and it is secured to the housing 10 as by screws 20 through holes 22 in the

2

cover member. The cover member 18 is provided with three openings 24 and a central opening 26 for admitting atmospheric air to the diaphragm 16. Several other minute openings 28 are also provided for admitting air to the diaphragm in the event that the central portion seals off the openings 24 and 26 by contact therewith. The entrance of this air is necessary, as ambient air pressure is desired on the outside of the diaphragm as opposed to the inner surface being subjected to the pressure of air in the lungs of the aviator.

The primary cover 18 is provided with three bosses 30 to which a secondary cover 32 is secured, as by drive screws 34. The secondary cover 32 has an inturned flange 36 at its periphery. This flange overhangs the openings 24 and is spaced slightly from the primary cover 18 to permit free entrance and exit of air to and from these openings.

The overhanging relation of the periphery of the cover 32 to the openings 24 prevents the direct rays of sun from passing through the openings and impinging the diaphragm 16. This is particularly important where the gas mask is used by a gunner in a gun blister on an airplane. The curvature of the blister tends to intensify the rays of the sun, and sun rays, of course, are detrimental to a diaphragm made of rubber or a similar composition.

The cover 32 also prevents the entrance of foreign objects through the openings 24 which might mechanically damage the diaphragm, and is a substantial aid in preventing the entrance of rain to the diaphragm, which is detrimental to its operation.

It will be obvious that I have provided a simple cover assembly which permits free flow of air to and from the diaphragm and yet prevents chemical and mechanical injury to the diaphragm from the result of sun rays or foreign objects which might otherwise pass through the atmosphere-admitting perforations of the main cover. The cover assembly may be modified to some extent without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a diaphragm cover of the character disclosed, a primary cover plate secured to the housing of an oxygen regulator over the diaphragm thereof, a plurality of bosses extending outwardly

from said primary cover plate, and a secondary cover plate secured to said bosses and having a peripheral inturned flange terminating in closely spaced relation from said primary cover plate, said primary cover plate having air entrance openings within the outline of said secondary cover plate and spaced inwardly from said flange.

2. In a diaphragm cover for oxygen regulators, a primary cover plate adapted to be secured to the housing of the regulator over the diaphragm thereof, a secondary cover plate connected to said primary cover plate, the connections including spacer elements to hold the two cover plates spaced apart for air entrance between them, said primary cover plate having air entrance openings within the outline of said secondary cover plate and communicating with the space between said plates and said secondary cover plate having a peripheral inturned flange

terminating in closely spaced relation from said primary cover plate.

JAMES P. JOHNSON.
